QUICK SEPARATION SLIDE FASTENER AND SLIDER STOP FOR THE SAME

John M. Sinclair, Warren, R. I., assignor, by mesne assignments, to Coats & Clark Inc., Wilmington, Del., a corporation of Delaware

Application March 14, 1952, Serial No. 276,492

6 Claims. (Cl. 24—205.11)

This invention relates to slide fasteners of the kind providing for a quick separation of the fastener stringers and to an improved stop for the slider of such fasteners. More particularly, the invention provides a fastener in which the slider can be quickly removed from one stringer, which in turn enables the latter stringer to be quickly separated from the other by a lateral pull. In normal use, the stop acts to check the normal movement of the slider thereover, but when the slider is drawn with more than normal force against the stop, the slider can be moved past the stop, thus enabling the stringers to be separated.

According to the invention, a fastener stringer is provided with a stop in the form of an elongated member enclosed within the edge of the stringer at a portion thereof on which scoops are mounted, the member extending longitudinally within the stringer edge over a distance occupied by at least several scoops and being concealed from view throughout its length. As a result, that portion of the stringer edge containing the member is stiffened so as to prevent the scoops adjacent the member from meshing with corresponding scoops of a companion stringer during normal coupling movement of the slider. However, the elongated member is sufficiently flexible to permit the scoops to mesh on more forcible movement of the slider, the slider being movable past the member during such movement.

Fasteners of the kind under consideration are desirable in a number of instances where a quick separation of the stringers is wanted, as in jackets, sleeping bags, coat linings, etc. Such stringers are usually provided with separable couplings, such as the pin and box type, at one end of the same to enable one stringer to be completely separated from the other. The invention, however, is not limited to fasteners having separable type couplings.

Among the objects of the invention is the provision of a fastener of the quick separation type in which the stop is not only simple and inexpensive but is concealed from view, the fastener appearance being virtually unchanged in this respect by comparison with conventional fasteners. Other objects and advantages will become apparent from the ensuing description.

A selected embodiment of the invention is shown in the accompanying drawing, in which:

Fig. 1 is a broken off view of a slide fastener incorporating the improved stop;

Fig. 2 is a view like Fig. 1 but showing the slider after it has been moved past the stop;

Fig. 3 is a broken off enlarged view, partly in section, illustrating the function of the stop for checking normal movement of the slider;

Fig. 4 is a view like Fig. 3 illustrating the slider in an intermediate position as it is being drawn past the stop; and

Fig. 5 is an enlarged sectional view taken along the line 5—5 of Fig. 1.

Referring to the drawings in detail, there is shown a pair of stringers 8, 9 comprising, respectively, tapes 10,

2

11 having beaded edges 12, 13 on which scoops 14 are mounted in spaced relation. A conventional flanged slider 15 having a pull 16 is mounted on the stringers for coupling and uncoupling the same. The invention does not require any particular form of slider or scoops. Stringer 8 at the upper end portion has a group 17 of scoops which extends beyond the end scoop 18 of the companion stringer. An end stop 19 is mounted on the end scoops of stringer 8 of the kind described and illustrated in U. S. Patent No. 2,506,965 to Morin. This end stop prevents the slider from passing off the stringer 8. On stringer 9 at a point 20 opposite the group 17 of scoops, a portion of the bead, beginning at a point adjacent the end scoop 18, may be removed to facilitate the withdrawal of this stringer laterally through the slider. Such removal of a portion of the bead is not necessary where the stringer is originally provided with a bead which passes laterally through the slider.

At 21 is shown an elongated pin embedded in the tape bead of stringer 9. The pin extends longitudinally within the bead over a distance occupied by several scoops and serves to stiffen the bead at that point. The pin should be long enough to function as a normal slider stop and to be sufficiently bendable when the slide is forcibly drawn past it. It may have any suitable cross-sectional shape, round being preferred. Any suitable material may be used for the pin which will enable it to remain stiff during normal operation of the slider and to bend during forcible movement of the slider past it. As an example, the pin may be made of music wire. Preferably, it should have a point 22 to facilitate entry into and passage through the bead, and it may or may not be provided with a head. In this connection, the removal of the bead at the portion 20 facilitates the entry of the pin into the bead at 23. The pin may be inserted in the bead in any way, conveniently by the use of a suitable machine, and preferably the upper end of the pin should be disposed a little below the bead end 23. The bead, of course, expands sufficiently to receive the pin.

The action or operation of the stop is as follows. As will be understood, in a conventional fastener as the slider is moved along the stringers to couple them together, or, so to speak, as the stringers pass downwardly in the slider from the double channel end to the single channel end, the coupling end portions of a pair of next adjacent scoops are spread away from each other slightly to permit the coupling end portion of a scoop on the opposed stringer to mesh with them. This spreading action of a pair of neighboring scoops is brought about by virtue of the fact that the stringers pass by a bend in the slider. In Fig. 3, this bend may be indicated as 24. To permit the bead to bend and the scoops to be spread, the bead, of course, must be flexible. In Fig. 3, the bead has been rendered inflexible to such an extent by the presence of the pin that the normal force exerted in moving the slider to couple the stringers is insufficient to flex the bead and thus spread adjacent scoops sufficiently to permit meshing. That portion of the bead at or below the lower end of the pin is flexible enough to permit the coupling end portion of scoop 25 to be spread away from the coupling end portion of scoop 26, so that the coupling end portion of scoop 27 on the opposing stringer can mesh with scoops 25 and 26. However, that portion of the bead enclosing the pin resists flexing by the normal action of the slider, and as a result the coupling end portions of scoops 26 and 28 are not spread sufficiently to permit scoop 29 of the opposed stringer to mesh with them. The slider is thus brought to a stop because the combined length of non-meshed scoops 29, on the one hand, and 26 and 28, on the other hand, is greater than the width of the slider at and adjacent the point 24, and the slider therefore can-

not be drawn past these non-meshed scoops in the ordinary way. Now if the slider is drawn upwardly in a more forceful manner than usual, the pin, and therefore the bead enclosing it, can be bent sufficiently to enable adjacent scoops to be spread apart as usual and to mesh with the appropriate scoop on the opposed stringer, as shown in Fig. 4. When the scoops are meshed, there is no bar to the movement of the slider beyond the end scoop 18 of the stringer 9. The slider may be moved upwardly as shown in Fig. 2 until its progress is stopped by the top stop 19. At this point the lower end of the slider will have cleared the topmost scoop 18 on stringer 9 and the latter stringer may then be pulled laterally through the slider and easily separated from stringer 8.

If desired, pins such as the pin 21 may also be placed within the bead of stringer 9 at one or more points below the upper end portion of the same. Such a construction will provide the advantages of a stop for checking normal movement of the slider at various places along the stringers as well as the advantage of still being able to couple or uncouple the stringers notwithstanding the presence of the pin or pins. On articles like jackets a variable neck opening may be provided by a fastener of such a construction. A pin may also be located at any intermediate point on stringer 9, or stringer 8, regardless of the form of end stop, top or bottom, which the stringer may have.

As has been noted, the invention provides a stop of the character described which is concealed from view and which thus improves the appearance of fasteners of this kind. A fastener incorporating the present stop can be sewn into a garment without the interference caused by other forms of stops, such as those of the flange-and-spring variety where the flange extends onto the tape a substantial distance. Also, the present fastener need only have about six scoops in the group 17 on stringer 8, whereas many conventional fasteners of this kind employ a greater number of scoops in this position. Since the stop action of the present fastener is due to the resistance to meshing of the scoops, the quality of the stop action which will be obtained is more uniform than on quick separation fasteners where the action depends on friction between the slider and a more or less resilient stop member.

Only one part is required for the present stop, and that is the stop itself. The assembly operation consists in inserting the stop in the bead, for which a machine of simple design can be used.

As noted, no particular form of scoop is required. Those shown are illustrative, without going into detail, of the scoops in the above-noted Morin patent, or in U. S. Patent 2,322,537 to Morin, and as appears in Fig. 5, these scoops are provided with an opening 30 in the coupling end portion 31, which opening is engaged by a suitable projection not shown.

In the light of the foregoing description, the following is claimed:

1. In a quick separation slide fastener comprising a pair of stringers having a slider mounted thereon for coupling and uncoupling the same, each stringer comprising a tape having a beaded edge with scoops spaced along said edge, one stringer having at the upper end portion thereof a group of scoops extending beyond the uppermost scoop of the other stringer and also having a stop at said upper end portion for preventing the slider from passing off the same, the improvement comprising an elongated pin embedded in the tape bead of said other stringer at the upper end portion thereof on which scoops are mounted, said pin extending longitudinally within the bead over a distance occupied by several scoops and being concealed from view throughout its length, said pin serving to stiffen the bead at said end portion to prevent the scoops of said stringers from meshing upon normal coupling movement of the slider toward said end portion, and said pin being sufficiently flexible.

to permit said scoops to mesh at said end portion upon more forcible movement of the slider, whereby said slider may be drawn past said pin to permit said other stringer to be drawn laterally through the slider and to be separated from the first stringer.

5 2. In a quick separation slide fastener comprising a pair of stringers adapted to be coupled and uncoupled by a slider, each stringer comprising a tape having a beaded edge with scoops spaced along said edge, one stringer having a stop at an end portion thereof for preventing the slider from passing off the same, the improvement comprising an elongated pin enclosed within the tape bead of the other stringer at an end portion thereof on which scoops are mounted, said end portion corresponding to the end portion of the first stringer, said pin extending longitudinally within the bead over a distance occupied by several scoops and being concealed from view throughout its length, said pin serving to stiffen the bead at said end portion to prevent the scoops of said stringers from meshing upon normal coupling movement of the slider toward said end portion, and said pin being sufficiently flexible to permit said scoops to mesh at said end portion upon more forcible movement of the slider, whereby said slider may be drawn past said pin to permit said other stringer to be drawn laterally through the slider and to be separated from the first stringer.

3. In a quick separation slide fastener comprising a pair of flexible stringers adapted to be coupled and uncoupled by a slider, each stringer having scoops spaced along the longitudinal edge thereof, and a stop on one stringer for preventing the slider from passing off the same, the improvement comprising an elongated member enclosed within the edge of the other stringer at an end portion thereof on which scoops are mounted, said member being normally stiff but flexible upon the application thereto of a flexing force, said member extending longitudinally within the stringer edge over a distance occupied by only a portion of the scoops on said other stringer, and being concealed from view, said member stiffening the stringer edge at said end portion and thereby preventing the scoops of said stringers from meshing at said end portion upon normal coupling movement of the slider toward said end portion, whereby said normal movement of the slider is checked, and said member being sufficiently flexible to permit said scoops at said end portion to mesh upon more forcible movement of the slider, whereby said slider may be drawn past said member to permit said other stringer to be drawn laterally through the slider and to be separated from said one stringer.

4. In a slide fastener comprising a pair of flexible stringers adapted to be coupled and uncoupled by a slider, each stringer having scoops spaced along the longitudinal edge thereof, and a stop on one stringer for preventing the slider from passing off the same, the improvement comprising an elongated member enclosed within the edge of the other stringer at a portion thereof on which scoops are mounted, said member being normally stiff but flexible upon the application thereto of a flexing force, said member extending longitudinally within the stringer edge over a distance occupied by only a portion of the scoops on said other stringer and being concealed from view, said member stiffening the stringer edge at said portion and thereby preventing the scoops of said stringers from meshing at said portion upon normal coupling movement of the slider toward said portion, whereby said normal movement of the slider is checked, and said member being sufficiently flexible to permit said scoops at said portion to mesh upon more forcible movement of the slider, whereby said slider may be drawn past said member.

5. In a quick separation slide fastener stringer wherein a flexible stringer length is adapted to be coupled and uncoupled to an opposed flexible stringer length by a slider, said stringer lengths having scoops spaced along the longitudinal edge thereof, the improvement comprising

ing an elongated stiffening member enclosed within the edge of a stringer length at an end portion thereof on which scoops are mounted, said member being flexible upon the application thereto of a flexing force, said member extending longitudinally within the stringer edge over a distance occupied by only a portion of the scoops on said stringer length and being concealed from view, said member stiffening the stringer edge at said end portion and thereby preventing the scoops of said opposed stringer length from meshing upon normal coupling movement of the slider toward said end portion, whereby said normal movement of the slider is checked, and said member being sufficiently flexible to permit said scoops at said end portion to mesh upon more forcible movement of the slider, whereby said slider may be drawn past said member to permit said one stringer length to be drawn laterally through the slider and to be separated from the opposed stringer length.

6. In a slide fastener stringer wherein a flexible stringer length is adapted to be coupled and uncoupled to another flexible stringer length by a slider, said stringer lengths having scoops spaced along the longitudinal edge thereof, the improvement comprising an elongated stiffening member enclosed within the edge of a stringer length

10 at a portion thereof on which scoops are mounted, said member being flexible upon the application thereto of a flexing force, said member extending longitudinally within the stringer edge over a distance occupied by only 15 a fraction of the scoops on said stringer length and being concealed from view, said member stiffening the stringer edge at said portion and thereby preventing the scoops of said stringer lengths from meshing upon normal coupling movement of the slider toward said portion, whereby said normal movement of the slider is checked, and said member being sufficiently flexible to permit said scoops at said portion to mesh upon more forcible movement of the slider, whereby said slider may be drawn past said member.
